United States Patent Office.

JOSEPH COLLETT, OF WILLIAMSBURG, NEW YORK, ASSIGNOR TO HIMSELF AND I. SMITH,

Letters Patent No. 67,027, dated July 23, 1867; antedated July 15, 1867.

IMPROVEMENT IN STEAM-ENGINE LUBRICATORS.

The Schedule referred to in these Letters Patent and making part of the same.

TO ALL WHOM IT MAY CONCERN.

Be it known that I, JOSEPH COLLETT, of Williamsburg, in the county of Kings, and State of New York, have invented a certain new and useful Improvement on Lubricators, of which the following is a full, clear, and exact description, reference being had to the accompanying drawing, forming part of this specification, and in which—

Figure 1 represents a front elevation of a lubricator constructed according to my improvement, and

Figure 2 a vertical section thereof, viewed at right angles to fig. 1.

Like letters of reference indicate corresponding parts throughout both figures.

My invention is applicable to various parts of engines or machinery in which the lubricating material or fluid has to be introduced to the parts to be lubricated against pressure, as of steam for instance, or wherever the normal pressure on the lubricating material in the reservoir of the lubricator differs from the pressure to which it is exposed at its discharge aperture. It will be sufficient here, however, to explain my invention, to describe it as a lubricator to an engine steam-chest or valve-chamber, and in this connection the nature of my invention consists, first, in a novel tubular construction of the interior of the lubricator, connecting the upper and lower portions thereof, so as to form a steam passage between the upper part of the reservoir and lubricating discharge-chamber, with a separate passage for the grease to the latter, and independent valves to the steam passage at top and grease passage below, whereby not only may a balance of pressure be produced above and below the lubricating material, but on opening the lubricator to the atmosphere both the escape of steam and discharge of grease are or may be automatically prevented, and this without disturbing the gauge or tap that regulates the discharge of grease when the lubricator is closed; and my invention further consists in so combining the stopper or cover of the reservoir with the valve to the steam-way that connects the upper and lower portions of the lubricator as that closing the stopper or cover opens said valve, which closes by the pressure of steam as said stopper is opened; and said invention further consists in a combination, with a general grease-discharge valve that opens and closes accordingly as pressure is thrown on or removed from it, of a separate regulating valve that may be worked by hand to open, adjust, or shut off the discharge of grease from the lubricator.

Referring to the accompanying drawing, A represents the reservoir of the lubricator into which the lubricating material may be inserted by an opening at its top, covered by a screw-stopper, B, or other suitable cover. C is the nozzle or discharge end that may be formed with a discharge-chamber, a, and delivery-aperture, b, and that may be connected to the reservoir A by an intermediate piece or connection, B, on to which the nozzle C and reservoir are screwed, the one above and the other below. This connection, D, has a vertical upward extension, E, terminating in a valve-seat, F, and which is formed with a passage, c c, running up through it and downwardly through the body of the connection so as to establish communication between the reservoir at or near its top and the discharge-chamber a. Said connection D also is made with a lateral arm, G, and with passages, d e f, the first one of which (d) runs longitudinally through the arm G, and at its inner extremity is made to form a valve-seat, so as, by the action of a screw-valve, H, to open or shut off communication between the other two passages (e and f) that connect, the one, e, with the reservoir, and the other, f, with the discharge-chamber a, and which latter passage, f, is opened or closed at its bottom by a loose valve, I, as the valve-seat F of the extension E is also opened or closed by a loose valve, J. The object of the valve H is to open or shut off or to regulate at pleasure the discharge of grease, and, by way of determining the amount of discharge, or giving it a fixed quantity, variable at pleasure, I mark on the face of the wheel g, by which the valve is operated, divisions or lines that, accordingly as they are made to change their position relatively to any fixed point, serve to show the amount of discharge taking place. Now, supposing the lubricator to be fixed in its place on a steam-chest or valve-chamber, and to be supplied with a proper quantity of grease, and the regulating valve H to be partially open, then it will be evident that steam entering by the aperture b into the chamber a finds its way by the passage c c and valve-seat F into the reservoir A above the surface of the grease, and thus a pressure from above is induced equal to that acting from beneath on the grease in the passage f, thereby producing a counterbalance which permits of the free discharge of the grease, as regulated by the

screw-valve H. The valve I, under this condition of things, remains open, as shown in the drawing, permitting of the softened or melted grease to pass beneath it, through side orifices in its bottom, into the aperture b, while the upper valve J is kept open by the screw-stopper. But supposing it to be desired, either for the purpose of putting fresh lubricating matter into the reservoir, or for any other reason, to open the lubricator while the engine is at work, then, on taking off the stopper or cover B, steam rushing up the passage e c closes the valve J, and accordingly prevents that escape which otherwise would take place, and which involves not only waste of steam but also interference with resupplying the reservoir. Furthermore, the reservoir A being thus freed from steam, the pressure from below closes the valve I against its seat in the passage f, thereby preventing the grease from being blown out; and this, it will be seen, is effected without of necessity closing the regulating-valve H or its adjustment to give a fixed discharge on closing again the cover or stopper B. Still it is not necessary, to shut off the discharge of grease, that the stopper B should be removed, as it may be done by closing the valve II.

This combination of an automatic and hand control of the lubricator will be found serviceable in numerous instances. Of course the shape or disposition of the several passages and forms of valves may be variously modified without departing from the principle of my invention.

What I claim as new and useful is—

1. The combination of the steam-way or passage e c and grease passage or passages e f, with their valves I J, arranged for action, in connection with the reservoir and grease outlet or discharge-chamber, substantially as specified.
2. The valve J to the steam-way or passage that admits steam to the upper portion of the reservoir, in combination with the stopper or cover to the lubricator, so arranged in relation thereto that said cover on being shut uncloses and retains open the valve, essentially as and for the purpose herein set forth.
3. In combination with the grease-discharge valve I, that closes by the action of the steam, the hand-adjustable valve II, for joint or separate action as herein set forth.

JOSEPH COLLETT.
